DESIGN FOR A DISPLAY STAND FOR PERFUME OR THE LIKE

Lewis M. Hathaway, New York, N. Y.

Application July 13, 1939, Serial No. 85,999

Term of patent 7 years

To all whom it may concern:

Be it known that I, Lewis M. Hathaway, a citizen of the United States of America, residing at New York, in the county of New York and State of New York, have invented a new, original, and ornamental Design for a Display Stand for Perfume or the like, of which the following is a specification, reference being had to the accompanying drawing, forming part thereof, and in which:

I claim:

The ornamental design for a display stand for perfume or the like, substantially as shown.

LEWIS M. HATHAWAY.
